UNITED STATES PATENT OFFICE.

JOHN E. MEGSON, OF CATSKILL, NEW YORK.

WIPER-RING FOR THE CYLINDERS OF INTERNAL-COMBUSTION ENGINES.

1,368,447.

Specification of Letters Patent. Patented Feb. 15, 1921.

Application filed January 3, 1920. Serial No. 349,157.

To all whom it may concern:

Be it known that I, JOHN E. MEGSON, a citizen of the United States, residing at Catskill, county of Greene, State of New York, have invented a certain new and useful Improvement in Wiper-Rings for the Cylinders of Internal-Combustion Engines, of which the following is a specification, reference being had to the accompanying drawing, forming a part thereof.

This invention relates generally to internal combustion engines and, more particularly, to a certain new and useful improvement in wiper-rings, so-called, for the cylinders thereof.

In internal combustion engines of the splash system of lubrication type especially, lubricant from the crank-case will, unless prevented, work up the cylinder wall and 20 find its way into the engine combustion or explosion chamber, the efficiency and proper operation of the engine being thereby detrimentally affected.

The chief object of my present invention 25 is to obtain the efficiency and proper operation of the engine being so affected, and with this and other objects in view, my present invention resides in the provision upon the piston, of a so-called wiper or auxiliary ring so constructed and co-operating with the piston and cylinder-wall as to form what might be designated or described as a seal between the piston and cylinder-wall against the lubricant working up the 30 cylinder-wall into the combustion-chamber, the ring carrying up with it on the upstroke of the piston only sufficient lubricant to properly lubricate the rubbing faces or surfaces of the piston and cylinder, and the ring 35 on the down-stroke of the piston wiping and removing from the cylinder-wall and leading or directing back into the crank-case any surplus or excess lubricant, and in the novel features of form, construction, arrangement, and combination of parts hereinafter described and afterward pointed out in the claims.

In the accompanying drawing,

Figure 1 is an elevational view of an engine-piston and wiper-ring constructed in accordance with and embodying my invention, the same being illustrated in operative connection with the cylinder shown in longitudinal section;

Fig. 2 is an inverted plan view of the ring, 55 the piston being indicated by dotted lines;

Fig. 3 is a cross-sectional view of the piston on approximately the line 3—3, Fig. 1; and

Fig. 4 is an enlarged transverse section of 60 the ring, operatively shown in connection with an enlarged fragmental section of the piston.

Referring now more in detail to the said drawing, in which like reference characters 65 indicate like parts throughout the several views, 1 indicates a cylinder of an internal combustion engine of any standard or approved splash system of lubrication type. Arranged for reciprocation in cylinder 1, is 70 a piston 2 provided near its upper or combustion-chamber end with suitable packing-rings 4, as is usual.

Suitably adjacent its lower or crank-case end, as seen in Fig. 1, the piston 2 is provided circumferentially with a peripheral annular groove 5. This groove 5 is preferably rectangular in section, as seen in Fig. 4, to accommodate the ring 8 hereinafter more fully described; but it will be seen 80 that a portion of the lower wall of the groove is cut away to provide the piston circumferentially with a beveled wall 6 which inclines or slopes inwardly toward the groove 5, the piston 2 being thereby circumferentially formed, for purposes shortly appearing, immediately next and in communication with the groove 5, with an annular oil or lubricant receiving or collecting basin. Formed in or upon the surface of the piston, 85 is a plurality or series of spaced longitudinal grooves or lubricant-ways 7, which communicate at their upper ends with the basin 6 and lead or drain from the basin 6 to the lower or crank-end of the piston. 90

Fitting in the groove 5, as seen in Figs. 1 and 4, is my new wiper-ring 8, which is also for the most part rectangular in transverse section, and which is preferably of eccentric split construction, as seen in Fig. 100 2, the ring being radially expansive and its ends overlapping, as shown. The ring 8 is further of such relative size to neatly and conveniently fit within the groove 5 and expansively bear and rub at the lower 105 part of its outer or front face against the cylinder-wall. The upper part of the front or outer face of the ring 8 is, however,

beveled off or cut away inwardly at an angle, as at 11, for purposes shortly appearing, the wall 11 merging at its opposite ends in gently rounded corners into the upper 5 face and the lower part of the outer face of the ring, as seen particularly in Fig. 4. Formed in the outer part of the lower or under face of the ring 8, is an annular groove 9 preferably of inverted V-shape in 10 section, the outer wall of the groove 9 intersecting the periphery of the ring and forming therewith at the lower outer edge of the ring an annular scraping knife-edge 10 facing the crank-case and over-hanging 15 the basin 6, the inner wall of the groove 9 terminating at the upper edge of the beveled wall 6 and forming a continuous and uninterrupted surface for the escape of lubricant.

20 By forming and shaping the upper part of the outer face of the ring 8 as described, I do away with all sharp corners on the outer face of the ring, except at the knife-edge 10, and provide a gradually increasing 25 clearance between the upper part of the outer face of the ring and the cylinder-wall, whereby, as will now be evident, on the up-stroke of the piston the ring 8 will, through or by its bearing or rubbing outer 30 face, carry up only sufficient lubricant to provide for proper lubrication between the rubbing faces of the piston and cylinder-wall.

On the down-stroke of the piston, any surplus or excess lubricant on the cylinder-wall 35 will be wiped or scraped therefrom by the knife-edge 10 and be received or collected in the groove 9, and in due course find its way or drain from the groove 9 to the basin 6 and through the ways 7 back into the 40 crank-case. By having the inner wall of the groove 9 coinciding with the beveled wall of the basin 6, the lubricant has a free passage 45 from the groove, and thus there is no possibility of too much lubricant being pocketed by projecting parts of the piston.

Thus, as described, by my new wiper-ring and piston-construction, the lubricant from the crank-case is most effectively sealed from 50 the combustion-chamber, and I have found from experience that by the use of my new wiper-ring and piston-construction, there is effected a large saving in lubricant, carbon in the cylinders and fowling of the spark-plugs greatly obviated, the efficiency of the 55 engine maintained, and the mileage obtained considerably increased.

I am aware that changes in the form, construction, arrangement, and combination of the several parts of my wiper-ring and piston-construction may be made and substituted for those herein shown and described without departing from the nature and principle of my invention.

Having thus described my invention, what I claim and desire to secure by Letters Patent is:

1. The combination with a cylinder of an engine, of a piston arranged to reciprocate in the cylinder, the piston being provided adjacent its crank-case end with a circumferential ring-receiving groove, the lower wall of the groove being partly cut-away to form a circumferential lubricant-receiving basin immediately next said groove, 75 and an expansive ring fitting in said groove and having a bearing against the cylinder-wall, the ring being provided on its under face and next its periphery with an inverted V-shaped annular groove, the outer wall of 80 the groove forming with the periphery of the ring an annular scraping-knife-edge, said edge over-hanging said basin and said ring-groove communicating directly with said basin, the piston being provided longitudinally with a series of spaced surface grooves leading from said basin to the crank-case end of the piston.

2. The combination with the cylinder of an engine, of a piston adapted to reciprocate in said cylinder and provided adjacent to its crank-case end with a circumferential ring-receiving groove, the lower wall of said groove partly cut away to form a circumferential lubricant-receiving basin next 95 to said groove, and an expansive ring fitting in said groove and adapted to bear against the cylinder wall, the ring being provided on its under face and next its outer periphery with an inverted V-shaped annular groove, 100 the outer wall of said groove forming with the periphery of the ring an annular scraping knife edge overhanging said basin, and the inner wall of said ring-groove coinciding with the wall of the basin and forming 105 a clear passage from said ring-groove to said basin, the piston being provided with longitudinal grooves in its outer face leading from said basin to the crank-case end of the piston.

In witness whereof I have signed my name to this specification.

JOHN E. MEGSON.
